UNITED STATES PATENT OFFICE.

GEORGE S. GOODWIN, OF CHICAGO, ILLINOIS, ASSIGNOR TO WALTER P. MURPHY, OF CHICAGO, ILLINOIS.

END REINFORCEMENT FOR BOX-CARS.

1,384,831.

Specification of Letters Patent. Patented July 19, 1921.

Continuation in part of application Serial No. 86,402, filed March 24, 1916. This application filed March 27, 1918. Serial No. 224,951.

To all whom it may concern:

Be it known that I, GEORGE S. GOODWIN, a citizen of the United States, residing at Chicago, in the county of Cook and State of Illinois, have invented certain new and useful Improvements in End Reinforcements for Box-Cars, of which the following is a specification.

My invention relates to the provision of a metallic reinforcement for the end walls of a railway box car, particularly for a box car largely constructed of wood but which may have metal draft sills and metal striking or buffer blocks, or equivalent structures; and a primary object of the invention is to provide a reinforcement for cars of this type comprising bars extending up the end walls of the car employed in conjunction with an end plate reinforcing structure, buffer blocks or striking castings and truss rods running the length of the car or other anchoring means, these elements being united together and the striking block being rigidly connected with the draft sills as is the universal practice in car under-frame construction, so that the elements of the reinforcing and rigidifying system, thus provided, for the body of the car will strengthen and fortify the car body against cargo thrusts, weaving strains and other forces and pressure tending to weaken and destroy the car body. As the invention is intended to supply a reinforcement for the repair of old cars as well as a construction to be used in the building of new cars, the embodiment shown in the drawing hereof involves a diagonal arrangement of the end wall reinforcing bars adapted for cars having truss rods not in line with the end posts; and it is a further object of the invention to provide an arrangement of parts which can be adapted, by slight changes, to various relative positions of the truss rods and end posts; the deviation from the vertical of the end wall reinforcing bars, where such deviation is necessary, depending upon the extent to which the truss rods of the car are outside of the lines of the end posts.

The invention consists of the new and improved constructions, arrangements and devices to be hereinafter described and claimed for carrying out the above stated

objects and such other incidental objects as will appear from the following description of a typical embodiment of the invention. 55

In the drawings annexed hereto, which show this embodiment,

Figure 1 is a view, in elevation, of the body of a railway box car.

Fig. 2 is a sectional plan on line 2—2 of Fig. 1.

Fig. 3 is a broken longitudinal sectional view of the car showing both ends thereof.

Fig. 4 is a view, in perspective, of the end plate brace, and 65

Fig. 5 is a detail section on line 5—5 of Fig. 1.

Like characters of reference designate like parts in the several figures of the drawings.

Referring to the drawings, 10 indicates the end sill of the car (the corresponding parts in Fig. 3 at opposite ends of the car are given the same reference numerals), 11 the end plate, 12, 12 the end posts, 13, 13 the diagonal end braces, 14, 14 the end girths, 75 15 the end sheathing, and 16, 16 the side plates, the construction and arrangement of these parts being common to railway box cars of this general type. As a part of its under frame the car is provided with channel bar draft sills 17, 17 and with buffer blocks which, in the preferred construction shown, consist of castings 18 secured to the end sills 10 by bolts 19 and are united to the draft sills by any suitable means, for example, by rivets 20. The draft sills function as a beam supporting in part the body of the car and taking the thrust of the couplers against the striking castings in the usual manner. The coupler shank is indicated in outline at 21, being supported by a carry iron 22 secured to the buffer plates by bolts 23.

The car is provided with two truss rods 24, 24 which extend the length of the car, 95 passing through bosses 25 formed on the buffer plates and being anchored thereto by nuts 26. To reinforce the end wall of the car I provide two reinforcing bars 27, at each end of the car. These members are 100 preferably Z bars. They are secured at their upper ends to the end plate 11 by bolts 28, to the upper girth 14 by bolts 29, to the end posts 12 by bolts 30, to the diagonal

braces 13 by bolts 31, and to the end sill 10 and to the buffer plate 18 by the truss rods 24 above mentioned, the flange 32 of the Z bar attached to the car wall intervening, in each case, between the end sheathing of the car and the buffer plate, as shown in Fig. 5, so that the truss rod on this side of the car will pass through this flange. In order to rigidify the end plate 11 an angular brace 33 (Fig. 4) is secured to the inner side of the end plate by the bolts 28 above referred to, these bolts passing through the middle section 34 of the brace. The ends 35 of the brace are secured by bolts 36 to the side plates of the car. By this arrangement the stresses on the reinforcing bars 27 are transmitted through the brace 33 to the side plates of the car.

A reinforcing structure consisting of the elements above noted in the arrangement as described, provides a strong, light and relatively inexpensive expedient for strengthening and rigidifying the entire body of a railway box car of wood construction and thereby checking the action of those destructive forces, such as the thrust of shifting cargoes, weaving stresses, and the like, which are constantly at work while a box car is in service and which, unless effectively checked, materially shorten the life of the car. The Z-bar end braces at each end of the car are anchored to the under frame by means of the buffer block, which is preferably but not necessarily a casting, and which, by bearing against the outstanding webs of the Z-bars and against the flanges thereof which lie along the sheathing, keeps the Z-bars from distortion and from being torn away from their attachment to the under frame. The upper ends of the Z-bars are anchored to the roof brace 33 through the end plate of the car so that there are provided unitary reinforcements for the end of the car which rigidify the entire superstructure.

This application is a continuation of my co-pending application Serial No. 86,402, filed March 24, 1916 (now Patent 1,282,568, granted October 22, 1918, reissued as No. 50 14,588 February 4, 1919).

I claim:

1. A reinforcement for the end wall of a railway box car comprising, in combination with the end plate, side plates, striking block and truss rods of the car: a pair of end braces on the outside of the end wall of the car and an end plate bracing structure within the car secured to the end plate and side plates thereof; the truss rods of the car extending through and being anchored to the lower extremities of said end braces and the latter anchored to the striking block, the upper ends of said end braces being connect-

ed with said end plate bracing structure through the end plate of the car. 65

2. A reinforcement for the end wall of a railway box car comprising, in combination with the wooden side plates, end plate, end posts and diagonal end braces of the car and with the striking block thereof: a pair of metal end braces on the outside of the end wall of the car extending diagonally from top to bottom thereof and attached to said end posts and also to said diagonal end braces, the lower ends of said end braces being anchored to said striking block, and an end plate bracing structure within the car secured to the end plate and side plates thereof to which the upper extremities of said end braces are connected. 70 75

3. A reinforcement for the end wall of a railway box car comprising, in combination with the end plate, side plates and striking block of the car: a pair of metal end braces Z-shaped in cross section on the outside of the end wall of the car extending from the under frame to the roof frame of the car and converging toward their upper extremities, the lower extremities of which are anchored to the under frame by said striking block, and an end plate bracing structure on the inside of the car comprising diagonal members extending from the center portion of the end plate to the side plates, to which structure the upper ends 90 95 of the braces are rigidly anchored. 100

4. A reinforcement for a railway box car comprising in combination with the wooden end wall of the car: a pair of end wall braces on the outside of the car extending from the roof frame to the under frame and converging toward their upper ends, a transverse element spacing the lower ends of the braces apart and anchoring them to the underframing of the car, and a roof frame bracing structure connecting the end wall to the side walls of the car to which the upper extremities of the end wall braces are rigidly anchored. 105

5. A reinforcement for a railway box car comprising in combination with the wooden end wall of the car and with the end sill of the car: a pair of end wall braces angular in cross section on the outside of the car extending from the roof frame to the sill and converging toward their upper ends, a striking block arranged between the lower ends of said end braces in the angle between the webs thereof for anchoring the end wall braces to the end sill, and a roof frame bracing structure connecting the upper portion of the end wall of the car to the side walls to which the upper extremities of the end wall braces are rigidly secured. 110 115 120

GEORGE S. GOODWIN.
